CLAIM

We claim the ornamental design for tread for a footwear lower, as shown and described.

DESCRIPTION

FIG. 1 is a bottom perspective view of tread for a footwear lower showing our new design;

FIG. 2 is a front elevation view thereof;

FIG. 3 is a rear elevation view thereof;

FIG. 4 is a bottom plan view thereof;

FIG. 5 is a left side elevation view thereof;

FIG. 6 is a right side elevation view thereof; and,

FIG. 7 is a top plan view thereof.

The broken line illustration of footwear in the figures is for illustrative purposes only and forms no part of the claimed design.
